UNITED STATES PATENT OFFICE.

HERMAN KLINGENBERG, OF FITCHBURG, MASSACHUSETTS.

FLOOR-BRUSH ATTACHMENT.

Application filed April 6, 1928. Serial No. 268,018.

This invention relates to an attachment for floor brushes for applying a sweeping compound to the floor in advance of the brush.

The principal objects of the invention are to provide such an attachment with a hopper for the sweeping compound having a valve which can be opened and closed readily and left in regulated position so as to deposit the proper proportion of sweeping compound on the floor and to provide the same with means for readily attaching it to the back of a floor brush and detaching it therefrom as desired. The invention also involves improvements in details of construction as will appear.

Reference is to be had to the accompanying drawings in which—

Fig. 1 is an end view of a floor brush with a preferred embodiment of this invention applied thereto;

Fig. 2 is a plan of the attachment showing the brush in dotted lines;

Fig. 3 is a transverse sectional view of the hopper and attachment; and

Fig. 4 is a bottom plan view of the hopper.

This attachment is designed to be applied to a floor brush having a horizontal back such as the back 10 shown in Fig. 1. This back is provided with a handle 11 and the attachment is applied on the opposite side of the back from the handle.

The attachment consists mainly of a hopper 12 fitted on the rear to conform to the shape of the convex back and project beyond it, so as to be of a general hopper shape. At the bottom, which is the smallest part of the hopper, is a bottom plate 13 having a series of perforations 14. It also has below it two guides 15 arranged horizontally. Between these guides and the bottom 13 is a slide or valve 16 having perforations 17.

The slide, when moved clear in, brings all the perforations 14 and 17 into registration with each other so that the floor compound can be discharged through them. When pulled out by its handle 18 into the position shown in Fig. 4, the perforations are brought out of registration as the space between the perforations is at least as wide as one of the perforations. It can be brought out only to this position on account of a stop 19 at the opposite end so when pulled clear out as far as it can go the operator knows that it will be in working order. He can make his adjustments as desired.

The top 20 of the hopper is hinged at the outer edge and catches under a central spring 21 which acts as a latch to hold it frictionally in closed position. This cover is provided with a handle 22 and it can be 60 swung open by force applied thereto and closed in the same way without releasing any latch with the other hand.

The hopper is provided with a pair of inwardly extending spring members 23 at its 65 inner side adapted to move under the edge of the back 10. It is also provided with spring latches 24 projecting over the back of the brush and having inwardly extending projections 25 adapted to spring in under this 70 edge of the back as shown in Fig. 1 to hold the device in position. The springs 24 can be made integral if desired with a strip 26 which extends along the back of the hopper and receives the edge of the cover 20 when 75 closed.

In use the floor brush is employed in the ordinary way but the valve plate 16 being moved out to open it the saw-dust compound is supplied to the floor by bringing the brush down on the floor to produce a slight jar. It is naturally a moist compound and will not feed very much, if any, without this being done. If it does feed without this jar action, the valve is closed a little to make the available openings smaller.

The device is applied to and removed from the back in an exceedingly simple manner being merely pressed down on it and the springs 24 if necessary forced down to apply 90 it and being removed by pressing on the projections 25.

This constitutes a very simple device for the purpose intended and one that can be applied very easily and when in position will 95 always have the floor compound ready to be applied to the floor and adapted to be deposited thereon simply by jarring it as by bringing the brush down on the floor with a slight blow.

Although I have illustrated and described only a single form of the invention, I am aware of the fact that modifications can be made therein by any person skilled in the art without departing from the scope of the 105 invention as expressed in the claims. Therefore, I do not wish to be limited to all the details of construction herein shown and described, but what I do claim is:—

1. In an attachment for a floor brush, the 110

combination with a hopper for receiving a sweeping compound, said hopper being detachably mounted to the back of the brush and positioned to dispense said compound in advance of the brush, said hopper having a bottom provided with a series of perforations and with a pair of guides located horizontally but spaced from the bottom below it, of a valve slidably located between the guides and the bottom and having a series of perforations so located that when the slide is forced in as far as it can be the perforations in the slide and bottom will be out of registration, the slide having a projection at one end for manipulating it and a stop at the other end for stopping it with the perforations in wide open position.

2. In an attachment for a floor brush, the combination with a hopper for receiving a sweeping compound, mounted to dispense said compound in advance of the brush and having a valve by which the bottom can be opened to provide for a deposit of a small

portion thereof on the floor and a cover on the hopper hinged thereto, of a strip along the edge of the hopper having a spring latch for holding the cover closed, and a spring extending from the hopper at each end adapted to engage the opposite edge of a brush back to detachably hold the hopper in position. 25 30

3. The combination with a brush back having a convex form, of a hopper therefor adapted to receive and to dispense sweeping compound in advance of the brush, and having hooks on the inner side adapted to project under the nearer edge of the brush back, and a pair of spring latches conforming to the shape of the brush back and projecting over it to the opposite edge and having projections adapted to swing in under the opposite edge of the brush back to hold it in position. 35 40

In testimony whereof I have hereunto affixed my signature.

HERMAN KLINGENBERG.
